UNITED STATES PATENT OFFICE

133,461

DESIGN FOR AN AUTOMOBILE SPOTLIGHT

Henry Rew Gross, Chicago, Ill.

Application December 2, 1941, Serial No. 104,430

Term of patent 14 years

To all whom it may concern:

Be it known that I, Henry Rew Gross, a citizen of the United States, residing at Chicago, Cook County, Illinois, have invented a new, original, and ornamental Design for an Automobile Spotlight, of which the following is a specification, reference being had to the accompanying drawing, forming a part thereof.

The characteristic features of my design reside in those portions shown in solid lines on the drawing.

I claim:

The ornamental design for an automobile spotlight, substantially as shown and described.
HENRY REW GROSS.
